UNITED STATES PATENT OFFICE.

JOHN LAFAYETTE MALONE, OF WHISTLER, ALABAMA.

HYDRAULIC JACK.

1,292,498.

Specification of Letters Patent. Patented Jan. 28, 1919.

Original application filed March 25, 1918, Serial No. 224,624. Divided and this application filed August 19, 1918. Serial No. 250,551.

To all whom it may concern:

Be it known that I, JOHN L. MALONE, a citizen of the United States, residing at Whistler, in the county of Mobile and State 5 of Alabama, have invented certain new and useful Improvements in Hydraulic Jacks; and I do declare the following to be a full, clear, and exact description of the invention, such as will enable others skilled in the 10 art to which it appertains to make and use the same.

My invention has for its object to provide a comparatively simple, yet a highly efficient and durable hydraulic jack intended 15 principally for removing piston rods from cross heads by the action of the hydraulic ram, the present application being divisional of my U. S. application, Serial No. 224,624, filed March 25, 1918, and allowed June 22, 20 1918.

One object of the invention is to provide novel means for returning the oil from the ram into the oil reservoir by the opening 25 of two check valves which are normally employed to prevent such return, this operation being effected by an abnormal movement of the operating handle.

Yet another object is to mount the operating handle or lever of the device on a 30 swiveled head so that its relation with the remainder of the device may be varied as most convenient.

With the foregoing objects in view, the invention resides in the novel features of 35 construction and unique arrangement of parts hereinafter fully described and claimed, reference being made to the accompanying drawings forming a part of this application.

Figure 1 is an edge view of the jack applied for removing a piston rod from a cross head.

Fig. 2 is a vertical longitudinal section of the jack.

Figs. 3 and 4 are transverse sections on the planes indicated by the lines 3-3 and 4-4 respectively of Fig. 2.

Fig. 5 is a view similar to Fig. 2 but illustrating the manner in which the valves are operated to return the oil to the reservoir from the ram, after operation of the device.

In the drawings above briefly described, the numeral 1 designates an elongated metal body preferably of substantially cylindrical

shape with its center enlarged at 2 and provided with flat sides. One end of body 1 forms a hydraulic cylinder 3 in which a hydraulic ram or plug 4 is slidably received, suitable packing means 5 being carried by the inner end of said ram or plug to prevent 55 the leakage of fluid. By the means yet to be described, the ram 4 is projected against the piston rod R after the body 1 has been anchored in the cross head C. For so anchoring the body 1, the latter is provided on 60 its opposite sides with abutments A adapted for reception in the usual wrist pin openings O of the cross head C, the construction and arrangement of these abutments being protected by the application above referred to.

The end of the body 1 remote from the cylinder 3 is formed with an oil reservoir 11 having a filling opening 12 normally closed by a vented plug 13 which will permit the 75 escape of any air from the reservoir without allowing the oil to leak therefrom. A central cylindrical bore 14 leads from the reservoir 11 into the cylinder 3, the end of said bore adjacent the cylinder being counter-bored and threaded at 15 to receive a plug

16 in which a check valve 17 is mounted to prevent the passage of oil from the cylinder 3 after it is once forced into the latter, said valve being closed by a spring 18 and having a spider-like stem 19 which extends beyond the inner end of the plug 16 for a purpose to appear. A plunger 20 is provided to force the oil from reservoir 11 into cylinder 3 in order to project the ram 4, said 90 plunger having a suitably packed piston 21 on its inner end received slidably in the bore 14. This piston is provided with ports 22 which upon each receding stroke of the piston, permit oil to enter the aforesaid bore 14 95 in advance of the piston, these ports however being closed on the power strokes of the piston by a spring-closed check valve 23 having a spider-like stem 24 slidable in the inner end of the plunger 20.

The intermediate portion of the plunger 20 slides through an appropriate stuffing box 25 and projects through a hollow head 26 which is swiveled at 27 to the end of the body 1 opposite the ram 4. The outer end 105 of head 26 is provided with a guide 26' through which the outer end of plunger 20 slides, said plunger having an external

shoulder 28 adapted to strike the inner end of said guide to limit the receding movement of said plunger. An operating lever 29 extends through a slot 30 in one side 5 of the head 26 and is provided with furcations 31 on its inner end receivable in notches 32 in the opposite sides of the plunger 20, whereby oscillation of said lever will reciprocate the plunger, thus forcing oil from the 10 reservoir 11 into the cylinder 3 and projecting the ram 4 to remove the piston rod R. Since the head 26 is swiveled to the body 1 and lever 29 is fulcrumed to said head, this lever may be swung around into the most 15 convenient relation with the device. To limit the proceeding movement of the plunger, a stop 33 preferably in the form of a set screw, is provided in the path of lever 29 as shown clearly in Fig. 2.

20 After operation of the device, it is necessary to return the oil or other fluid used from the cylinder 3 to the reservoir 11. In order to accomplish this, it is necessary to withdraw the stop 33 sufficiently to permit 25 an excessive movement of the piston 21, with the result that this piston will strike the stem 19 and open the check valve 17 (see Fig. 5). At the same time, it is necessary to open the 30 valve 23 and in order to attain this end, a stem 34 is housed in the plunger 20, the inner end of said stem being arranged to strike the stem 24 of said valve 23 while the outer end of said stem 34 is provided with a plug or head 35 threaded into a socket 36 in the 35 outer end of the plunger. When this plug or head is so turned as to force the stem 34 inwardly as shown in Fig. 5, the valve 23 will be held in open position. Then, by inverting the entire device (see again Fig. 5) 40 the oil will flow from the cylinder 3 back into the reservoir 11.

In operation, the body 1 is inserted in the cross head while the abutments A are in retracted position, said abutments being then 45 withdrawn and suitably adjusted to adapt them to the size of the wrist pin openings O. This having been done, the lever 29 is oscillated so that the plunger 20 forces oil into the cylinder 3 to project the hydraulic ram 50 4 against the piston rod, thus forcing the latter from the opening in which it has been held. To remove the device, the abutments A are again forced into the body 1 and after such removal, the oil is returned to the reservoir 11 by inverting the device and opening

the check valves in the manner above set forth.

From the foregoing, taken in connection with the accompanying drawings, it will be obvious that although my invention is of comparatively simple and inexpensive nature, it will be highly efficient and reliable. Since probably the best results are obtained from the several details shown and described, these details are preferably employed, but within the scope of the invention as claimed, considerable latitude is allowed for development.

I claim:

1. A device of the class described comprising a body having therein a reservoir, a hydraulic ram carried by one end of said body, a plunger for forcing fluid from said reservoir to actuate said ram, an actuating lever for said plunger, and a hollow head swiveled to the end of the body opposite said ram, and receiving one end of said plunger, said lever being fulcrumed to said head, and the latter having a slot through which the lever extends into the head, the connection between the lever and plunger being housed in said head.

2. A device of the class described comprising a body having a reservoir, a hydraulic ram at one end of said body, a plunger for forcing a fluid from said reservoir to operate said ram, an operating lever for said plunger, said plunger having a fluid port and a check valve controlling the same, a second check valve to prevent return of the fluid from said ram, extreme movement of said plunger serving to open said second check valve, and means independent of said lever for then opening said first named check valve to permit the fluid to return to the reservoir.

3. A structure as specified in claim 2, said check valve opening means comprising a stem movable longitudinally through said plunger, and screw-threaded means for shifting said stem.

4. A structure as specified in claim 2, said check valve opening means comprising a stem movable longitudinally through said plunger, and a head on said stem threaded into said plunger for moving said stem to either position.

In testimony whereof I have hereunto set my hand.

JOHN LAFAYETTE MALONE.
